UNITED STATES PATENT OFFICE.

WILLIAM A. BUTLER AND ADOLPH KUNZE, OF SAN FRANCISCO,
CALIFORNIA.

CONTINUOUS KILN.

SPECIFICATION forming part of Letters Patent No. 703,533, dated July 1, 1902.

Application filed September 20, 1901. Serial No. 75,984. (No model.)

To all whom it may concern:

Be it known that we, WILLIAM A. BUTLER and ADOLPH KUNZE, citizens of the United States, residing in the city and county of San

5 Francisco, State of California, have invented an Improvement in Continuous Kilns; and we do hereby declare the following to be a full, clear, and exact description of the same.

Our invention consists in the novel arrangement of pipes, combustion-chambers, and passages hereinafter fully described and specifically pointed out.

The object of our invention is to provide for the economical use of fuel-oil or powdered coal for burning bricks and other ware in continuous kilns.

Referring to the accompanying drawings for a more complete explanation of our invention, Figure 1 is a longitudinal vertical section. Fig. 2 is a longitudinal horizontal section. Fig. 3 is a transverse vertical section.

A, Fig. 1, represents the kiln in which the bricks or other ware are to be burned; B, B', and B², Fig. 1, combustion-chambers below 25 the floor of kiln, with openings or slot C, Fig. 1, connecting the combustion-chamber with the kiln.

D and D', Fig. 3, are the burners, and E, E', and E², Fig. 3, are the pipes through which 30 fuel-oil or powdered coal is introduced into the combustion-chambers.

G, G', and G², Fig. 3, are horizontal flues or pipes connecting the combustion-chambers and running longitudinally under the kiln- 35 floor.

H and H', Fig. 1, are the draft-flues connected with the longitudinal flues G, G', and G².

The fuel-oil or powdered coal introduced into the combustion-chambers is converted 40 into gas, which rises to the openings in the floor of the kiln to the bricks or other ware which are to be burned.

The supply of fuel-oil or powdered coal is controlled from the top of the kiln by suitable compression-cocks connected with the pipes which are fitted around top of kiln. The said pipes run down from the top of the kiln through the walls or filling between walls or outside of the kiln-walls and into the combustion-chambers. 45

The openings into the combustion-cham-

bers from the top or side, through which the pipes pass, are made so as to exclude air not required for blowing in the fuel from entering at these points.

55 A continuous kiln works economically only when the feed-air enters the open portion of the kiln where the burned brick or other ware are being taken out, passes through the cooling bricks or other ware, becoming 60 hotter in its passage, until it is consumed by the fuel, and is finally carried up the chimney of the kiln as spent gas and water-smoke.

The object of the flues or pipes G, G', and G² is to draw the heat from one combustion-chamber to another by the flame passing 65 through said pipes or flues, to equalize the heat in the kiln, to feed oxygen into the combustion-chamber by drawing feed-air from the open chamber through and under-

70 neath the bricks or other ware previously burned, to promote perfect combustion and to cool the bottom of the kiln after the fire has passed and the bricks or other ware are burned, so that the workman can work with- 75

out inconvenience from heat. The said flues G, G', and G² are connected in each chamber by a cross draft-flue leading to a damper connected with the draft-stack of the kiln. A paper partition is placed at each cross draft- 80

flue, closing the area of the kiln-tunnel, making a stopping-point for the draft till the fire has advanced another section when the paper is burned out. To make the draft stop 85 at the same point in the longitudinal flues below kiln-floor, we place a small paper partition on each longitudinal flue at the side of the cross-flue that the large paper partition above is on.

In some continuous kilns fuel-oil or powdered coal is introduced through the top or crown of the kiln. As gas from fuel naturally ascends, the heat must be drawn through the kiln with a strong downdraft, which brings the gases down to the kiln-floor and out of 90 the kiln before perfect combustion has taken place. In other continuous kilns there are combustion-chambers which admit fuel and feed-air into the sides of the kiln. This method is a waste of heat, as the heat of the 95 cooling bricks or other ware already burned

cannot be drawn through the fire as it should 100

be and must necessarily be allowed to escape and because the cold air admitted into the combustion - chambers requires additional heat to bring it up to the proper temperature 5 for combustion.

The devices composing our improvement are not only simple and inexpensive, but more useful and more effective than any other contrivance heretofore employed for a kindred 10 purpose.

Having thus described our invention, we claim and desire to secure by Letters Patent—

1. A continuous kiln having a series of combustion-chambers extending crosswise below kiln-floor in which liquid or powdered fuel is burned in suspension, communicating directly with the kiln by means of openings in kiln-floor and combined with longitudinal 15 flues or pipes below kiln-floor and between the longitudinal walls of the kiln, connecting said combustion-chambers, substantially as described.

2. A continuous kiln comprising combustion-chambers extending crosswise and below kiln-floor, in which fuel is burned in suspension, connected with the kiln by means of openings across said floor and joined by flues or pipes running horizontally underneath said 20 floor, connecting said combustion-chambers, and joining damper-controlled draft-flues, substantially as described.

3. A continuous kiln having a series of combustion-chambers extending transversely 25 and below kiln-floor connected with the kiln by means of openings across said floor and joined by passages below said floor connecting said combustion-chambers and communicating with damper-controlled draft-flues;

combined with fuel pipes or flues leading to 40 the top and to the outside of the kiln, for the purpose of supplying fuel to the combustion-chambers, substantially as described.

4. A continuous kiln comprising combustion-chambers extending crosswise and below 45 kiln-floor, in which fuel is burned in suspension; with a series of openings across kiln-floor connecting said combustion-chambers with the kiln, joined by flues or pipes below kiln-floor connecting combustion-chambers and 50 communicating with damper-controlled draft-flues; combined with pipes flues and burners for the introduction of fuel, said pipes and flues running to the top and outside of the kiln through and between the kiln-walls substantially as described.

5. A continuous kiln having a series of combustion-chambers running across and below kiln-floor in which fuel is burned in suspension, joining one another by means of horizontal pipes or flues below said floor, said pipes or flues communicating with damper-controlled draft-flues; said combustion-chambers connected with the kiln by means of openings across kiln-floor combined with 60 pipes and flues running to the top and outside of the kiln, for the introduction of fuel; means of controlling the supply of fuel from the top and outside of the kiln substantially as described.

In witness whereof we have, this 27th day of August, A. D. 1901, set our hands.

WM. A. BUTLER.
ADOLPH KUNZE.
